LIGHT MODULATION SYSTEM

Henry Shore, Elizabeth, N. J., and James N. Whitaker, Tuckahoe, N. Y., assignors to Radio Corporation of America, a corporation of Delaware

Application May 26, 1934, Serial No. 727,689

6 Claims. (Cl. 179—171)

The present invention relates to picture transmission systems and finds application principally in connection with facsimile and television transmission of pictures and other similar and related subjects.

The invention also finds application in other arts, such, for example, as color sorting, smoke detection, meter reading, light control apparatus, electric sign control, and other associated and allied arts.

For the purpose of illustration, however, the invention has herein been applied to the picture transmission art in order to illustrate one of the many general applications thereof.

As a primary object of the invention, we have sought to provide a system in which the fidelity of picture transmission and the like will be improved and wherein the resulting output will be linear as a function of the density of the subject of which an electro-optical reproduction is desired.

As a further object of the invention, we have sought to provide a light conversion system which will be relatively insensitive to supply voltage fluctuations and, therefore, to provide a device wherein increased stability of operation is inherent.

As a further object of the invention, we have sought to provide a system for converting varying intensity light values into electrical signals which, due to its extreme stability, will hold in adjustment without change for long periods of time so that especially in connection with the transmission of pictures re-runs may be made without the loss of time for readjustment and thereby save considerable circuit time.

As a further object of the invention, we have sought to provide a light modulating system wherein great simplicity of operation and manipulation for optimum conditions of operation is inherent.

Further objects and advantages of the invention will be pointed out in connection with the description of the apparatus illustrated and described herein and still other objects and advantages will naturally suggest themselves to those skilled in the art to which the invention is directed by reading the following description and claims in connection with the accompanying drawing wherein the single figure thereof illustrates schematically one of the many forms which our invention may assume.

Referring now to the drawing, and bearing in mind that the invention herein described is illustrated in connection with only one of its many forms of application, where it is desired to trans-

mit pictures, there is provided a record carrying drum 1 bearing the record strip or picture 3. Preferably the drum is rotated by any desired and suitable form of drive such, for example, as has been illustrated in United States Patent No. 1,803,133 granted to R. H. Ranger on April 28, 1931. When the facsimile drive is set up as above suggested, light from any suitable and desired source 5 is focused by means of an optical system 7 at a point 9 on the record surface. The reflected light of the picture subject at the point 9 is then directed by means of a second optical system 11 to influence the light-sensitive electrode of a light converting means conventionally indicated by the photoelectric cell 13. The photoelectric cell 13 has one of its electrodes, preferably the light-sensitive cathode thereof, connected to influence the parallelly connected grid or control electrodes of the vacuum tube 15. The tube 15, as are all other tubes disclosed herein, is preferably of the type known in the art as the 79 tube which is of the general type combining within one bulb two high-mu triodes. The other electrode of the photoelectric cell 13 is arranged to connect with the parallelly connected grid or control electrodes of a second tube 17 of the same general type as the tube 15.

Voltage is supplied to the electrodes of the photocell preferably from a common voltage divider so that the cathode of the photocell connects, for example, to a negative point 19 on the voltage divider by way of the secondary winding 21 of the transformer 22 and the resistor 23, whereas the positive electrode of the photocell 13 connects to a point 25 more positive than the point 19 by way of a second secondary winding 27 of the transformer 22 and the resistor 29.

The grid electrodes of the tubes 15 and 17 are also supplied with alternating current of a predetermined carrier or tone frequency which is connected to the terminal points 31 so as to flow through the primary windings 33 of the transformer 22. The secondary windings 21 and 27 of this transformer are preferably reversed with respect to each other so that, for example, when the upper end of the secondary winding 21 is positive due to the alternating current voltage supplied at the terminal points 31, the lower end of the winding 21 will also be positive. The output or plate electrodes of the tubes 15 and 17 also are connected in parallel and connect with the grid electrodes of the tube 35 by way of the conductor 37 and capacity 39 and conductor 41 and capacity 43, respectively. Plate voltage is supplied to the tube 15 from the common volt-

age divider 31 by way of a phone jack 45 and a resistor 49 which connect to the terminal point 25. The tube 17 is supplied with plate voltage from the same voltage divider 31 by way of the 5 resistor 51 and phone jack 53 connected to a point 55 thereof. The tube 17 has its plate voltage maintained higher than that of the tube 15 as is obvious from the connection shown. The cathode electrode of the tube 15 is connected to 10 a point 57 on the voltage divider, whereas the cathode of the tube 17 is connected to a point 59 on the voltage divider 31.

The output current from the tube 35 which is connected push-pull fashion flows through the 15 primary winding 61 of the transformer 63 so as to induce in the secondary winding 65 thereof suitable voltages which can be measured by means of a meter 67 connected across the secondary winding. At the output terminals 69 20 connection may be made to a suitable type of load circuit in the form of a recorder or to a transmitter of either the radio or the wire type. Plate voltage for the tube 35 is supplied by a connection at point 71 to the common voltage 25 divider 31. The point 71 is maintained as the highest point in the system and the opposite end of the voltage divider 31 is preferably grounded at a point 73.

In order to supply heating current for all of 30 the tubes 15, 17 and 35, a separate heater circuit conventionally indicated as 75 is arranged to supply all heater elements in parallel and is preferably energized from a suitable source which has been conventionally indicated as an 8-volt 35 source.

When a device of the type herein disclosed is operating, it will be seen that the system disclosed is that of a balanced grid modulator which is followed by a single stage of push-pull amplification. In the balanced grid modulator comprising the tubes 15 and 17 the tone to be modulated which is applied at the terminal points 31 is fed to the grids of the modulator tubes in like phase. These tubes 15 and 17 are arranged to 45 have essentially the same bias and this bias is purposely made high so as to operate in the curved region of the grid voltage-plate current characteristic. If the tubes 15 and 17 are identical the carrier tone causes an equal rise and 50 fall of potential in the plate circuit of each tube. The fact that the plates are coupled together in anti-phase relation causes the two potentials to buck out each other so that the output current is normally zero.

55 The modulating signal supplied by way of the light modulation influencing the photoelectric cell 13 actuates the grids of the tubes 15 and 17 in push-pull and serves to decrease or lower one grid potential while the potential of the other 60 grid is raised, and since the tubes 15 and 17 are assumed to be operating in the curved region of the characteristic, changes in grid potential cause the amplification factor of the tube to vary, increasing negative potential, for example, causing a decrease of gain and vice versa. Consequently, the modulating voltage by raising the 65 amplification in one tube produces an unbalance of voltages in the plate circuit. It follows, then, that since the two voltages are no longer equal a 70 voltage equal to the difference between the two plate voltages is now available as the output. This difference in voltage is proportional to the shift in grid potential over a relatively large range and accounts for linearity of output as a 75 function of input.

In the particular form in which the invention has been illustrated, the modulating potential is supplied by the voltage drop across the high resistance units 23 and 29 in series with the photo-cell 13 and its supply voltage as determined by 5 the portion of the voltage divider between the points 19 and 25. By using a split resistor and suitable biasing voltages equal drops in voltage are supplied to the two modulator tubes in opposite phase and so perform the duty of modulation. In order to raise the output to any desired degree the modulated carrier tone may then, as shown, be amplified by a single or multiple push-pull stage and it will be appreciated that this arrangement furnishes a means by which the 10 output may be kept free from harmonics and furnishes a wave across the terminal point 69 which is generally of a pure sine wave shape.

While we have illustrated by the accompanying drawing only one suitable form which our invention may assume, it is, of course, to be understood that the said invention may assume and take many varied forms without departing from the spirit and scope of this disclosure and we therefore believe ourselves to be entitled to make 20 and use any and all of these modifications which would at once suggest themselves to those skilled in the art insofar as such modifications and changes fall fairly within the invention as defined by the hereinafter appended claims.

Having thus described our invention, what we 30 claim and desire to secure by Letters Patent is the following:

1. A light controlled modulation system comprising a plurality of pairs of thermionic devices 35: each having control grid and plate circuits parallelly connected, a photoelectric cell having its light sensitive cathode connected to one pair of parallelly connected control grids and its anode connected to the other pair of parallelly connected control grids, a source of carrier frequency, a plurality of circuits each including independent resistance and inductance elements for supplying voltages to the photoelectric cell, said inductance elements also serving as reversely wound secondary transformer windings, means including said transformer windings for introducing A. C. voltages of instantaneous like sign upon the electrodes of said photoelectric cell and each pair of parallelly connected control grid elements so that 40: said A. C. is modulated by voltage changes on the control grids due to variations in light on the photocell and so that stray capacity of the photoelectric cell to ground is reduced to a minimum, and a load circuit for amplifying the produced 45: modulations.

2. A modulation system comprising a unidirectional signal energy source, a pair of thermionic devices having control electrodes, input 60: circuits and output circuits, said thermionic devices having their input circuits connected in opposite phase with the said source, a source of carrier frequency connected in like phase with said thermionic devices, a balanced impedance input means for supplying carrier frequency to the said thermionic devices connected in opposite phase so as to reduce the stray capacity to ground to a minimum value, a common voltage supply for all of said devices, means for supplying independently variable biasing voltages to the 65: control electrodes of the thermionic devices from the common voltage supply, and a load circuit connected with the output circuit of said thermionic devices.

3. The modulation system claimed in claim 2 75:

wherein said load circuit comprises a pair of push-pull connected thermionic devices connected with the output circuit of said first-named thermionic devices.

- 5 4. In a modulation system, a light responsive electrical device, a plurality of series connected impedance elements connecting between the anode and cathode of the light responsive device, parallelly connected thermionic devices having 10 control electrodes, input circuits, and output circuits, said parallelly connected thermionic devices having their input circuits connected with the two end portions of the series connected impedance elements so that the light responsive device 15 varies the output energy from each parallelly connected thermionic device in dependence to the intensity of light impinging upon the light responsive elements to vary the voltage drop through the said series connected impedance, a 20 single power supply for energizing the thermionic devices, means to supply independently variable biasing voltages to the parallelly connected control electrodes from the single power supply, means for impressing upon each of the parallelly 25 connected thermionic devices a carrier frequency to produce like changes in voltage on the control electrode of each, a balanced impedance means for supplying said carrier to each of said parallelly connected thermionic devices to reduce 30 stray capacity to ground to a minimum value, means to determine the change in output energy from each pair of parallelly connected thermionic devices, and a load circuit connected with the output of said first thermionic devices.
- 35 5. In a modulation system, a light responsive electrical device, a plurality of impedance elements comprising series connected resistances and transformer secondaries connected across the light responsive device output, parallelly connected thermionic devices having control electrodes, input and output circuits, said thermionic devices being coupled to the electrode of the light

responsive device and the end terminal points of the series connected impedance elements so that the input of each parallelly connected thermionic device rises and falls in dependence to its connection in accordance with the light actuating 5 the light responsive element, a single power supply for energizing the thermionic devices, means to supply independently variable biasing voltages to the parallelly connected control electrodes from the single power supply, means for impressing upon all of the parallelly connected thermionic devices a carrier frequency to produce like changes in voltage on the control electrode of each, a balanced impedance means for supplying said carrier to each of said thermionic devices 10 to reduce stray capacities to ground to a minimum, and a load circuit including a pair of push-pull connected thermionic devices connecting with the parallelly connected output of said first-named thermionic devices. 15

20 6. A modulation system comprising a uni-directional signal energy source, a pair of thermionic devices having control electrodes, input circuits and output circuits, said devices having their input circuits connected push-pull fashion with 25 the uni-directional signal energy source, a source of carrier frequency connected in like phase with each of said thermionic devices, and a balanced impedance input means for supplying the carrier to the said push-pull connected thermionic devices, a single power supply for energizing the thermionic devices, means to supply independently variable biasing voltages to the control electrodes of the thermionic devices from the 30 single voltage supply whereby output energy from the thermionic devices either increases or decreases in accordance with increasing output energy from the uni-directional signal energy source, and a load circuit connected with the output circuit of said thermionic devices. 35 40
